UNITED STATES PATENT OFFICE.

MARGARET EMILY RHODA DOUGLAS, OF LONDON, ENGLAND.

TRAVELING HEADDRESS.

Application filed June 15, 1923. Serial No. 645,498.

To all whom it may concern:

Be it known that I, MARGARET EMILY RHODA DOUGLAS, of Old Cavendish Street, London, W. 1., England, a subject of the King of Great Britain and Ireland, have invented certain new and useful Improvements in and Relating to Traveling Head-dress, of which the following is a specification.

- 10 This invention relates to a traveling head-dress and has for its object to provide an improved construction of such articles designed more particularly for the use of ladies when motoring and adapted to be firmly and comfortably secured on the head without disturbing the hair and at the same time to protect the ears and facial nerves against being hurt by the rushing contact with the air while traveling at speed.
- 15 My improved construction of traveling headdress of the above indicated kind is distinguished by the features, that at the sides of the crown or head band means are provided for securing ear pieces carried
- 20 by a piece of elastic or the like which may be fastened under the chin of the wearer in any desired manner, while the back brim is constructed to support a hood of any suitably light material in such a manner as to
- 25 cover the said ear pieces and the back fastening of face veil when worn, and generally to assist in securing the headdress on the head.

When a double back brim is used the hood is preferably secured to or held in place by the upper, and the face veil fastening is supported by the lower, back brim.

Examples of a traveling headdress made in accordance with the invention are illustrated in the accompanying drawings, in which

Fig. 1 is a perspective view of a wire foundation for the shape, including the front brim, and a lower back brim; this figure also shows ear pieces arranged adjacent to their correct position relatively to the brims;

Fig. 2 is a similar view of the upper back brim;

50 Fig. 3 is a similar view of a suitable crown adapted to surmount the foundation parts shown in Figs. 1 and 2;

55 Fig. 4 illustrates the whole "shape" made from the assembled parts shown in Figs. 1 to 3, including a face veil, and a hood secured to the back brim;

Fig. 5 shows an alternative method of attaching the ear pieces.

Referring to Figs. 1 to 4 of the drawings, in the arrangement shown a wire 1 is bent into a circular form as a foundation for the "shape" of a hat. The brims, which may be of any suitable material are then cut out and stretched to the required shape. A second wire 2 is then bent to form the edge 60 of the front brim 3 and also the edge of the lower back brim 4, the wire 2 being secured to the edges of the said brims, and also being secured to the wire 1 at the sides 65 of the foundation, as shown. The upper back brim 6 (Fig. 2) may be formed of a material similar to that used for the front brim 3, or of any other desired and suitable material, the upper edge of the same being defined and stiffened by means of a 70 wire 7 bent round to form approximately a semi-circle, to which the material of the upper back brim is secured.

75 The foundation of the crown 8 (Fig. 3) may be of any suitable material.

80 The upper back brim 6 may be secured upon the back part of the foundation above the lower back brim 4 by attaching the ends of the wire 7 to the sides of the foundation, 85 formed as shown in Fig. 1, so that the ends of the wire 7 are firmly secured to the side junctions of the wires 1 and 2. The arrangement is such that a space 10, of about three inches, is left between the ends of the lower back brim (or the point where the 90 wire 2 forming the edge of the lower back brim is bent away from the wire 1) and the adjacent ends of the front brim 3, this space accommodating hooks 11 and 12 which are secured at the sides of the foundation about

95 half an inch from the ends of the front brim to receive the eyelets 13 and 14 fixed to the upper ends of ear pieces 15 and 16 respectively, the lower ends of the ear pieces being conveniently connected by a piece of 100 elastic 17 adapted to be passed under the chin. In this arrangement the barbs of the hooks 11 and 12 are passed under the connected wires 1, 2, and 7 so as to come outside and enable the eyelets 13 and 14 to be 105 easily hooked on or removed at will. If desired however the ear pieces 15 and 16 may be permanently attached to the foundation at the spaces 10.

If the lower back brim is not required, 110 the hooks 11 and 12 must still be attached as described above.

Fig. 4 shows the foundation parts illustrated in Figs. 1, 2, and 3 assembled together to form the "shape" of the hat with the ear pieces 15 and 16 in wearing position. 5 The hat may naturally be completed by the addition of any desired adjuncts, trimmings, and the like of various materials to suit individual taste. A face veil 18 may be worn or not as desired. When worn this 10 veil may conveniently be semi-circular in shape, the upper or straight edge being mounted on an elastic band 19 adapted to pass over the front brim 3 and to be fastened with a clip at the back where it is 15 supported by the lower back brim 4. The hood 20 (Fig. 4) is a straight or shaped piece of material which will vary in width and depth according to the size or style of the hat. The upper edge of the hood can 20 either be sewn to the edge of the upper back brim 6, or may be mounted on a piece of elastic adapted to be passed over the said brim and secured by clips to the head band, or the ends of the piece of elastic may be 25 sewn together to form a circle which is passed over the crown and secures the hood in such a manner that when the ribbon ends 21, 22 provided on the hood are tied under the chin, the hood completely covers 30 and hides the ear pieces 15 and 16 and the back fastening of the veil 18. The lower edge of the hood 20 is also threaded through with a piece of narrow elastic terminating in bone rings 28 and 29 through which the 35 ribbon ends are passed.

Fig. 5 shows an arrangement of the kind described just above in which the hood 20' is strung upon a piece of elastic formed into a circle adapted to be passed over the crown 40 of the hat. In this case the ear pieces 15 and 16 may be sewn directly to the elastic 23, the ear pieces being so arranged relatively to the hood that they are covered by the hood when the parts are assembled for 45 wear.

When the hat is secured on the head with a veil and hood as described above no fastenings can be seen and the head and face of the wearer are completely protected from 50 dust, glare, wind, and weather. The appearance of the whole hat is attractive and business-like and the hat has been tested and found very satisfactory in use. The

ear pieces protecting the ears from wind pressure are a great comfort to travellers 55 who suffer from headache or strain, while the veil and hood are an almost complete protection from the dust and dirt inseparable from a long journey from road. The improved headdress is also very suitable for 60 yachting or for wear on a sea voyage and is quite neat in appearance without the veil and hood. It can be used for other purposes as well as for traveling and may naturally be very much elaborated in various 65 details, for instance, in the shape of the crown, brims, and other parts, which may be adapted to suit individual taste, but without varying the main principle of the improved construction as stated hereinabove. 70

What I claim and desire to secure by Letters Patent is:—

1. A headdress comprising a crown, a band attached to the crown adjacent its lower edge, a wire attached to and encircling 75 the lower edge of the band, a front peak and a rear peak attached to the lower edge of the band, a wire extending around the lower edge of the peaks, a semi-circular brim attached to the rear of the crown, a wire extending around the upper edge of the brim, a veil overlapping the front peak and having its ends secured together at the rear of the crown, and a depending hood attached to the brim, overlapping the rear peak and 80 covering the veil fastening means. 85

2. A headdress comprising a crown, a band attached to the crown adjacent its lower edge, a wire encircling the lower edge of the band, a front peak and a rear peak attached 90 to the lower edge of the band, wire reinforcements attached to the lower edge of the peaks, a semi-circular brim attached to the rear of the crown, a wire reinforcing the upper edge of the brim, ear pieces attached to 95 the band, an elastic cord attached to the ear pieces adapted to pass under the chin of the wearer and to hold the earpieces in position, a veil overlapping the front peak and having its ends secured together at the rear of 100 the crown, and a hood attached to the brim, overlapping the rear peak, and covering the ear pieces. 105

In testimony whereof I affix my signature.

MARGARET EMILY RHODA DOUGLAS.
